ABSTRACT OF THE DISCLOSURE

An arrangement for the wide-band coupling of the main spiral line of a travelling-wave tube with an essentially metallic tubular vacuum-tight envelope to a coaxial line, serving for the feed-in or lead-off of high-frequency energy, mounted perpendicularly to the tube, with the outer conductor of the coaxial line being extended to and merged in the metallic envelope, while the inner conductor of the coaxial line is conductively connected over the transformation spiral with the last coil of the main spiral characterized by the feature that the pitch and diameter of the transformation spiral is greater than that of the main spiral, said transformation spiral comprising at least one section and having, at least section-wise, constant pitch, said transformation spiral comprising a conductor having substantially uniform cross-sectional dimensions throughout its length.

The disclosure

The invention relates to an arrangement for wide-band coupling of the spiral line of a travelling-wave tube with an essentially metallic tubular vacuum-tight envelope to a coaxial line serving for the feed-in or lead-off of high-frequency energy, in which the coaxial line is mounted perpendicularly to the tube, with the outer conductor thereof extended to and merged in the metal envelope, while the inside conductor of the coaxial line is conductively connected over a spiral conductor portion (transformation spiral) with the last or end coil of the spiral line.

In travelling-wave tubes it is a known practice to couple the spiral line to a coaxial line serving for the feed-in or lead-off of high-frequency energy, in which coaxial line to the inner conductor is directly connected conductively with the end of the spiral line. The outer conductor of the coaxial line is connected, in the known arrangements of this type, with a cylindrical metal body which surrounds the spiral end portion. This cylindrical metal body, whose inner surface is generally horn-shaped or conical, should be designed and arranged in such a way that the smallest distance of the spiral from the inner surface of the metal body is less than a quarter of the axial wavelength at the corresponding point of the spiral.

In the known arrangements described, the required small distance between the metal body and the spiral necessitates very close tolerances and thereby leads to technological difficulties. In order to reduce this difficulty, it is a known practice to artificially enlarge the axial wavelength of the spiral in the region of the transition portions to the coaxial line, by increasing the pitch of the spiral therat. In order to achieve an adaptation, as good as possible, of the spiral to the inner conductor of the coaxial line, it is necessary for the transition from the portion of increased pitch at the end of the spiral to the normal pitch of the spiral line to gradually become smaller and smaller. This necessitates the utilization

of a spiral portion with variable pitch. The technological expenditure for an adequately precise manufacture of such a spiral portion with gradually changing pitch, however, again is very great.

The invention is directed to the problem of creating a wide-band coupling of the spiral line of a travelling-wave spiral tube to a coaxial line without great technological expenditure. For the solution of this problem, in an arrangement of the type heretofore mentioned, it is proposed according to the invention, that the transformation spiral with a constant pitch, which in a manner in itself known, has a pitch greater than the pitch of the spiral line (main spiral), and a diameter greater than that of the main spiral, so that the conductor forming the transformation spiral extends at a considerably smaller distance from the metal envelope than the conductor forming the main spiral.

An arrangement according to the invention has the important advantage that there is required merely a single transformation member between the coaxial line and the spiral line, in the form of a transformation spiral of constant pitch, which may be simply and inexpensively produced. This transformation spiral can be dimensioned in simple manner as a strip line according to high-frequency technology, which has as base conductor the metal vacuum envelope of the tube.

In the drawing, wherein like reference characters indicate like or corresponding parts:

FIG. 1 is a longitudinal section of the cathode end of a travelling-wave tube with a coupling device according to the invention; and

FIG. 2 is a transverse cross section thereof.

While FIGS. 1 and 2 illustrate sections of only the cathode end of a travelling-wave tube, the uncoupling device at the collector end of the tube would, in principle, be constructed in the same manner.

In the drawings, those parts of the tube which do not appear necessary for an understanding of the invention, such as, for example, the support clamping of the main spiral and transformation spiral, have been omitted.

The helix or spiral 1, herein designated as the main spiral, which is to be coupled to the coaxial line 2, is coaxially surrounded by a metal tubular vacuum-tight envelope 3. The outer conductor 4 of the coaxial line 2 is sealed vacuum-tight, for example, by a ceramic ring 5, is extended to and merged directly in the metal vacuum-tight envelope 3 of the tube. The inner conductor 6 of the coaxial line 2 is conductively connected directly with the adjacent end of a short transformation spiral 7, whose other end in turn is conductively connected with the end coil of the main spiral 1. The transformation spiral 7 has a greater pitch and a greater diameter than the main spiral 1, with the pitch and the diameter of the transformation spiral 7 being constant. The end of the transformation spiral 7, which, like the main spiral 1 can be supported under elastic deformation between three insulating bars bearing directly on the envelope 3, is integrally connected with the main spiral 1. The transformation spiral 7 and the main spiral 1 advantageously comprise a conductor in the form of a band, dimensions of which are the same for both spirals.

The wave impedance of the transformation spiral 7 can, with a given width b of the conductor band forming the spirals, in a simple manner be adjusted by suitable selection of the distance h from the metal envelope 3 whereby the usual known transformation condition is fulfilled. The transformation spiral can here be treated, in high frequency technology, as a strip line in which the envelope of the tube is the base conductor and the conductor band of the transformation spiral is the strip conductor. Consideration in this manner is practically

always possible if the distance h of the conductor band from the base conductor is considerably smaller than the pitch P_t of the transformation spiral 7. A strip line, as is well known, has an extremely wide-band, so that the entire coupling device has wide-band characteristics.

The invention is not limited to the embodiment illustrated. In particular, it is possible for the transformation spiral to be subdivided into several sections which have diameters differing from one another. It has also been proved that an especially good, wide-band adaptation of the coupling device is attainable if the transformation spiral 7 consists of two sections, of which the section directly connected with the inside conductor of the coaxial line has a greater diameter than the section which is adjacent to the main spiral. There are thus obtained two successively connected strip lines of different wave impedance, the wave impedance again being selected in dependence upon the known transformation conditions involved.

Changes may be made within the scope and spirit of the appended claims which define what is believed to be new and desired to have protected by Letters Patent.

We claim:

1. An arrangement for the wide-band coupling of the main spiral line of a travelling-wave tube with an essentially metallic tubular vacuum-tight envelope to a coaxial line, serving for the feed-in or lead-off of high-frequency energy, mounted perpendicularly to the tube, with the outer conductor of the coaxial line being extended to and merged in the metallic envelope, while the inner conductor of the coaxial line is conductively connected over a transformation spiral with the last coil of the spiral

windings characterized by the feature that the pitch and the diameter of the transformation spiral are greater than those of the main spiral, said transformation spiral comprising at least one section and having section-wise, constant pitch and constant diameter, said transformation spiral and said main spiral comprising a band-shaped conductor having substantially uniform cross-sectional dimensions throughout its length.

2. An arrangement according to claim 1, wherein the distance from the metal envelope of the conductor forming the transformation spiral is smaller than the pitch of the transformation spiral.

3. An arrangement according to claim 2, wherein the transformation spiral consists of two sections which have different diameters from one another, the section adjacent to the coaxial line having a greater diameter than the section of the transformation spiral which is adjacent to the main spiral.
